UNITED STATES PATENT OFFICE.

RICHARD WEBB BURNETT, OF MONTREAL, QUEBEC, CANADA.

AIR-BRAKE-PIPE HANGER FOR RAILWAY-CARS.

1,070,770.

Specification of Letters Patent. Patented Aug. 19, 1913.

Application filed March 20, 1911. Serial No. 615,808.

To all whom it may concern:

Be it known that I, RICHARD W. BURNETT, a citizen of the United States, residing in Montreal, in the Province of Quebec and Dominion of Canada, have invented a new and useful Improvement in Air-Brake-Pipe Hangers for Railway-Cars, of which the following is a specification.

My invention relates to improvements in anchoring devices for attaching air brake pipes or other longitudinal pipes to cars.

For efficient operation of air brake mechanism of railway cars, it is very important that the longitudinal train pipe should be very securely anchored to the car to prevent strain upon the angle cock couplings and connections of the air brake mechanism when the cars are subjected to severe shocks from bumping and switching and other use.

The object of my invention is to provide an improved construction of air brake or train pipe anchoring device for railway cars, which will be simple in construction and thoroughly efficient and reliable in operation.

My invention consists in the novel construction of parts and devices and in the novel combinations of parts and devices herein shown and described and more particularly specified in the claims.

In the accompanying drawing forming a part of this specification, Figure 1 is a front elevation of my improved train pipe anchor, the train pipe being shown in section. Fig. 2 is a longitudinal section on line 2--2 of Fig. 1 and Fig. 3 is a detail elevation, looking from the line 3--3 of Fig. 1.

In the drawing, 1 represents the needle beam or other portion of a railway car frame and 2 the air brake pipe extending through an opening 3 in the needle beam or frame member and which is to be anchored thereto.

My improved anchor comprises an anchor plate or disk 4 secured by rivets 5 to the needle beam or frame member 1, and provided with an integral hub or sleeve portion 4^a which is furnished with one or more, preferably two, longitudinally extending key slots 6, having inclined or wedge faces 7 to receive the wedge keys 8, each of which has a straight, horizontal face 9 for engage-

ment with the train pipe and an inclined or wedge face 10 for engagement with the inclined or wedge face 7 of the key slot 55 in the anchor disk or plate 4. The opening 3 in the needle beam or frame member 1 is made large enough to receive the train pipe 2 and also the wedge keys 8. The opening 11 in the anchor plate or disk 4 is preferably made only slightly larger than the train pipe or just large enough to admit of the easy and convenient insertion of the train pipe through the anchor plate. The wedge keys 8 have at their straight or longitudinal faces an extended bearing against the train pipe and at their wedge or inclined faces 10 against the anchor plate, and thus serve to very securely hold and lock the train pipe against longitudinal movement in 70 respect to the car frame. The ends 12 of the wedge keys 8 may be bent at an angle to lock them in position.

I claim:

1. A train pipe anchor for railway cars, 75 comprising an anchor plate secured to the car frame and provided with an integral extended hub furnished with a wedge faced slot and a wedge key having a straight, unbroken face for engagement with the train 80 pipe, said face being in engagement with the pipe throughout its entire length, and an inclined face for engagement with the inclined face of the key slot in the anchor plate, said key extending beyond both ends 85 of the hub and having its inner end adapted to be bent to prevent the same from accidentally falling out.

2. A train pipe anchor for railway cars, 90 comprising an anchor plate secured to the frame and provided with an integral extended hub furnished with a pair of wedge-faced slots, and a wedge key in each of said slots, each key having a face for engagement with a pipe passing through said hub 95 and an inclined face for engagement with the inclined face of one of said slots in the anchor plate, said keys extending beyond both ends of the hub, substantially as specified.

RICHARD WEBB BURNETT.
